UNITED STATES PATENT OFFICE.

JOSEPH E. LAWRENCE, OF WOLCOTT, NEW YORK, ASSIGNOR TO FLORIDA E. LAWRENCE, OF WOLCOTT, NEW YORK.

BURIAL APPARATUS.

SPECIFICATION forming part of Letters Patent No. 741,583, dated October 13, 1903.

Application filed October 20, 1902. Serial No. 127,996. (No model.)

To all whom it may concern:

Be it known that I, JOSEPH E. LAWRENCE, a citizen of the United States, residing at Wolcott, in the county of Wayne and State of New York, have invented a new and useful Burial Apparatus, of which the following is a specification.

This invention relates generally to burial apparatuses, and has for its object to provide a device by means of which a coffin or casket can be lowered into the grave by means of one man, who can also regulate the speed of descent.

A further object of my invention is to provide an adjustable frame, so that the device can be quickly and easily adjusted to fit around various-size graves and to accommodate caskets of different sizes.

Another object of the invention is to provide a device which shall be ornamental in its character, and thereby relieve the grave-opening of its gruesome aspect.

A still further object of the invention is to provide a suitable case in which the apparatus can be conveniently packed and carried as a part of the undertaker's outfit.

With these and certain other objects in view, as will hereinafter appear, the invention consists in the novel features of construction, combination, or arrangement, all of which will be fully described hereinafter and pointed out in the claims.

In the drawings forming part of this specification, Figure 1 is a perspective view showing my invention as applied to a grave. Fig. 2 is a view showing one end of the apparatus. Fig. 3 is a view showing one corner of the ornamental screen being set in place, said screen being omitted from the other views. Fig. 4 is a horizontal sectional view taken through one end of the apparatus, disclosing the operating mechanism. Fig. 5 is a transverse sectional view on the line 5 5 of Fig. 4. Fig. 6 is a sectional view on the line 6 6 of Fig. 4. Fig. 7 is a detail view of the operating-lever and treadle connected therewith. Fig. 8 is an inverted plan view of the said treadle. Fig. 9 is a sectional view on the line 9 9 of Fig. 11. Fig. 10 is a detail view of the detachable tension device. Fig. 11 is a view, partly in section and partly in elevation,

illustrating the tension device connected to the supporting-strap for holding the casket. Fig. 12 is a similar view showing the catch detached from the said supporting-strap. Fig. 13 is a view illustrating the sectional supporting-bar adapted to roll on and support the coffin or casket prior to being deposited upon the supporting-straps by means of which it is lowered into the grave. Fig. 14 is a plan view of the said sectional supporting-bar. Fig. 15 is a view of the entire apparatus arranged in the case. Fig. 16 is a detail perspective view of the lever employed for operating the lowering mechanism to raise or adjust the latter. Fig. 17 is an enlarged elevation, partly broken away, of the operating-lever, showing in dotted lines the position of the several parts when the latch is disengaged from the segment. Fig. 18 is an enlarged detail section drawn on about the line 18 18 of Fig. 17, and Fig. 19 shows detail of the several parts shown in Figs. 17 and 18.

In carrying out my invention I employ an adjustable rectangular frame A, which is adapted to be supported upon brackets B, arranged adjacent to the edge of the grave, so that the said frame will surround the grave and will be held a slight distance above the mound of the same, as most clearly indicated in Fig. 2. The adjustable frame A is preferably constructed of tubular metal material and comprises telescopic side members A', telescopic end member A² at one end, and a telescopic member A³ at the opposite end. The end members A² and A³ each have tubular connections A⁴, which are arranged at right angles to the members A² and A³ and adjacent to their ends, said tubular connections serving to receive the end sections of the side members A'.

By arranging the end and side members of the frame to telescope, as described, the frame can be readily adjusted to encircle the grave, it being only necessary to pull upon or press in upon the said members, when they will readily slide within one another until the required size is obtained, after which the members are securely fastened by the thumb-screws a, as shown in Figs. 1 and 15 of the drawings.

A spool C is arranged centrally within the

tubular member A³, said spool having a tubular shaft C' rigidly connected thereto, and surrounding the said spool is a strip of leather C², and embracing the said leather strip is a metallic brake-band C³, one end of which is rigidly connected to a shaft C⁴, the end of which projects through the tubular member A³. A sleeve C⁵ is arranged upon this shaft C⁴ and is adapted to turn thereon, the inner end of the said sleeve being threaded and adapted to engage the threaded portion of the said shaft, so that when the sleeve is turned in one direction the brake-band will be tightened upon the leather strip and will be loosened when moved in a reverse direction. Shafts D are fitted into the tubular shaft C'. Said shafts D extend in opposite directions and pass through suitable filling-plugs E, said shafts having ratchet-wheels E' at their outer ends, which are adapted to be engaged by the pawls E², said pawls and ratchet being protected by the cap-piece E³, arranged upon the end of the member A³. These caps E³ are removable, so that the shafts may be engaged and operated by a ratchet-lever E⁴, Fig. 16, which is adapted to be slipped upon the ratchets E' and operated for adjusting or re-winding the cables by hand and raising the casket out whenever it should be found necessary.

Each shaft D has a drum F mounted thereon, said drum being arranged opposite the tubular extension A⁴, and passing around the said drums are the cables G and H, the cable G passing over guide-pulleys G' and the cable H over a guide-pulley H', said guide-pulleys being mounted upon a threaded shaft H², so that as the cable is wound or unwound the said pulleys will move along the threaded shaft, so as to properly place the cables upon the drum F. The cable G passes around the guide-rollers G², carried in the tubular extension A⁴ adjacent to the member A³, and out through openings G³, produced in the sides of said extensions A⁴. The cable H passes out through the extension A⁴, through the side members A', and out through an opening H³, produced in the tubular extension A⁴, connected to an end member A². These cables G and H pass over a horizontal roller I, carried by a curved plate I', having hooks I², adapted to engage openings produced in the side of the said extensions A⁴, and each curved plate I' has an adjustable tension I³, which is regulated by means of a screw I⁴ and wing-nut I⁵, said tension-plate being adapted to bear upon the cable as it passes over the roller I, and by tightening or loosening the winged nut I⁵ the tension can be increased or decreased, as desired, preventing recoils. The outer end of each cable has an anchor-block K connected thereto, said blocks having springs K' connected to their upper ends. Each anchor-block K is also provided with two laterally-extending portions K², which are adapted to engage the cam-shaped heads

K³ of the catches K⁴, which are adapted to engage the end pieces K⁵ of the supporting straps or webs K⁶, and it should be stated here that these straps or webs are preferably constructed of leather and have their ends firmly riveted between the end pieces K⁵. The heads K³ of the catches K⁴ are pivoted within a housing K⁷, through which the cables pass, and it will be noted that when any weight is placed upon the supporting-straps and the catches engage the end pieces K⁵ the springs K' are compressed and the heads K³ engage the lateral extensions K². The moment, however, the weight or tension is removed the springs K' throw the anchors or blocks K downwardly, releasing the heads K³ and throwing the catches K⁴ out of engagement with the end pieces K⁵, and when thus released the straps may be readily withdrawn from under the casket, it of course being understood that only one end of the straps are released; but for appearances both ends are made to simulate each other. The sleeve C⁵ has a squared spindle-shaped outer end, to which a ratchet-wheel L⁷, having a bore to fit said spindle, is attached. The wheel L⁷ has a hub L⁸, to which side plates of levers are pivotally or revolvably connected. Between said lever-arm plates are the two pawls L⁶, pivotally hung and adapted to engage the wheel L⁷, thus connecting said lever-arm L to wheel L⁷. The pawls are pivoted adjacent each other and intermediate their ends, their end portions diverging, their inner ends engaging teeth on the wheel L⁷. The free end of said lever-arm carries a rack-segment L', which is adapted to be engaged at different points on the segment by a spring-actuated pawl L², arranged upon the under side of the treadle L³, pivoted to a bracket L⁴, extending downwardly from the outer end of the shaft C⁴. A spring-actuated bolt or pawl L² has an upwardly-extending heel-piece L⁵, against which the heel can be placed for the purpose of withdrawing the bolt or pawl out of engagement with the rack-segment L', and by means of this bolt or pawl when engaged and the treadle I am enabled to move the lever-arm L up or down, thereby increasing or decreasing the pressure upon the brake-band, and consequently regulating the speed of descent.

The lever L comprises two plates bolted together, one of said plates being broken away in Fig. 17 to show the mechanism located between them. On the outer end of the sleeve C⁵ is formed a squared spindle L⁹. The pawls L⁶ are adapted to be forced into engagement with the ratchet-wheel by an arm L¹⁰, carrying a wedge-shaped head L¹¹. This head rests between diverging outer ends of the pawls, and when the head is forced inward the ends of the pawls engaged by the head are forced apart and the inner ends are brought nearer together. A rod L¹² passes between the plates downward to a point below the bracket L⁴. The lever L is formed with a curved tapering

end which is pivotally connected to the central part of the rod L¹², the upper end of the rod being curved forward and being pivotally connected to a link L¹³, which is pivoted between the plates of the lever. A longitudinal slot is produced in the lower end of the link, the arm L¹⁰ being connected to the link by a pin passing through the slot. The spindle L⁹ has a square bore, in which fits a shaft C⁴, having a squared end L¹⁵, over which fits the upturned end of the bracket L⁴. C⁴ is perforated and threaded, and a threaded screw having an end cap fits in same and holds the bracket L⁴ in position. A slot L¹⁴ is produced in the foot-treadle, through which the rod L¹² projects. Pins L¹⁶ project from the bolt L² and actuate the rod, swinging it back and forth as the bolt is moved. When lever L¹⁰ is drawn back, the pawls disengage the ratchet, a guard L¹⁷, secured to the head L¹¹, being adapted to draw the rear ends of the pawls together. When the guard is drawn back, the lever L can be raised or lowered without the pawls engaging the wheel, and after actuating the lever-arm the foot can be pressed forward, returning the rod L¹² to its normal position, and the wedge-head L¹¹ will force the pawls into engagement again with the ratchet-wheel and also the bolt with the segment. Then the lever-arm is forced to rise sufficiently, and the cables unwind from their spools, lowering the coffin into the grave, and the moment the bottom is reached, the pressure being removed from the blocks K, they will become disengaged from the supporting-strap.

To facilitate the placing of the coffin upon the supporting-straps K⁶, I employ sectional supporting-bars M, which are pivotally connected to the side members, and at their inner ends said sectional supporting-bars are provided with interlocking heads M', held in engagement by a bolt M², adapted to be operated by a hand-lever M³. Each bar carries a roller M⁴ upon the upper face thereof, upon which the coffin or casket is rolled, it being understood that the said bars are moved together and interlocked, as most clearly shown in Fig. 13, just before the coffin is rolled thereon, and after the coffin has been rolled thereon the hand-lever is operated, disengaging the bolts and permitting the sectional supporting-bars to drop down, as clearly indicated in Fig. 1. This leaves the casket resting upon the supporting-straps K⁶, and the lowering operation then takes place, as already described. In order to conceal the mechanical appliances and also render the appearance of the grave less objectionable, I surround the same with ornamental screens resting against the supporting-brackets and held thereto in any suitable manner; but in the present instance the lower ends of the brackets are shown as bent back upon themselves, so as to provide a rest for the screen. It is thus seen that I provide a strong, durable, and efficient apparatus by

means of which a coffin can be slowly and evenly lowered into a grave.

From the foregoing it will be readily seen that I provide an exceedingly-simple and highly-efficient apparatus for the purpose specified, and by providing the end and side members to telescope into each other the frame may be quickly and easily adjusted to fit various-sized graves, as from the extreme large size of seven feet three inches by three feet to four feet three inches by one foot ten inches and all intervening sizes.

Having thus described my invention, what I claim as new, and desire to secure by Letters Patent, is—

1. In a burial apparatus, the combination with the central spool surrounded by a strap of leather, a brake-band adapted to engage the leather strap, the threaded rod and adjustable sleeve for operating the brake-band, the ratchet-wheel rigidly connected to the sleeve, a lever inclosing said wheel the rack-segment connected to the lever, a pivoted treadle and the spring-actuated locking-bolt connected to said treadle, as and for the purpose described.

2. In a burial apparatus the combination with the supporting-straps having end pieces, of the pivoted catches provided with heads and adapted to engage the said end pieces, the housing into which the catches are pivoted, the cables passing through the tops of said housing, the block arranged upon the end of said cable, and provided with laterally-projecting extensions, and springs connected to the block and adapted to bear upon the upper portion of the housing, as specified.

3. In a burial apparatus the combination with the tubular member having openings, of the guide-rollers arranged in said member, a cable extending through said member and passing through the opening, a detachable plate carrying a roller, and the adjustable tension-plate adapted to bear upon the cable, as specified.

4. In a burial apparatus, the sectional supporting-bars carrying rollers and provided with the interlocking ends, one of said bars having a bolt adapted to secure the interlocking ends in engagement and the lever for disengaging said bolt, as specified.

5. A burial apparatus comprising a tubular end member, a spool mounted therein, a brake-band around the spool, a shaft connected thereto, a sleeve thereon, a lever formed of two parallel plates rigidly secured to said sleeve, a ratchet-wheel secured between the lever-plates, pawls carried by the lever and adapted to engage said ratchet, a segment carried by the lever, a foot-treadle, and a bolt carried by the foot-treadle adapted to engage said segment.

JOSEPH E. LAWRENCE.
